UNITED STATES PATENT OFFICE.

WILLIAM L. McDougall, of NEW YORK, N. Y.

DEVICE FOR LOCKING WHEELS.

SPECIFICATION forming part of Letters Patent No. 298,051, dated February 5, 1884.

Application filed June 30, 1883. (No model.)

To all whom it may concern:

Be it known that I, WILLIAM L. McDougall, a citizen of the United States, residing at New York city, in the State of New York, 5 have invented certain new and useful Improvements in Devices for Locking the Wheels of Vehicles; and I hereby declare the following to be a full, clear, and exact description of the same, reference being had to the accompanying drawings, wherein—

Figure 1 is a side view of a buggy with my devices applied. Fig. 2 is a perspective view of the devices. Fig. 3 is a sectional view of a modification of the extensible joint of the 15 coupling-rod.

Like letters refer to like parts wherever they occur.

My invention relates to the construction of devices for coupling the wheels of vehicles, so 20 as to prevent their rotation, and, by hampering the movement of the same, preventing the ready removal of the vehicle or such accidents as arise from the starting off of teams which have been left standing. The general principle depends on reducing the vehicle to a drag by coupling together the wheels, for which 25 purpose I employ an extensible coupling rod or bar having at each end a wheel clamp or yoke, the adjustable parts of the rod and the 30 wheel-yokes being constructed substantially as will hereinafter more fully appear.

I will now proceed to describe my invention, so that others skilled in the art to which it appertains may apply the same.

35 In the drawings, A indicates a vehicle; B, the front and C the hind wheels thereof, to which the devices have been applied to lock the same.

D indicates the locking or wheel-coupling 40 device. Said device may consist of a single coupling-rod provided at each end with a yoke for holding the wheel, said yoke constructed substantially as hereinafter specified, which will be sufficient if no adjustment of the 45 devices is desired; but preferably the coupling-rod is composed of two sections, d d', connected by a sliding or telescopic joint, which may be formed by a sleeve on one section, (see Fig. 3,) or by two perforated lugs, e e', one at 50 tached to the end of each section d d', forming a guide for the other section, and provided with set-screws s, by means of which the rods

can be secured when adjusted to the desired length. On the end of each rod-section is a wheel-yoke, f, which is preferably of U form, 55 closed by a tongue or keeper, g, which is pivoted on one arm of the U, and provided at its extremity with a spring-lock, which engages with the other arm of the yoke. This lock, where it is desired to guard against unauthorized interference, may be a Yale or other 60 spring-lock requiring a key to operate it; but for all ordinary purposes the spring-catch shown—viz., a sliding pin, i, and spring k, with thumb-piece—or equivalent devices, may 65 be employed. It is desirable to bevel the end of the fixed arm of the yoke, and also the face of the spring-pin i, as shown in the drawings, in order to facilitate the engaging of the parts.

In order to prevent injury to the paint of 70 the fellies, I incase the arms of the yoke and the tongue or keeper g in sleeves h, of rubber or other soft protective covering material.

To prevent loss or displacement, this locking device is generally secured to the side of the 75 vehicle by a light chain, and hooks m m may be provided for suspending the coupler D at the side of the bed when not in use.

The device may be made of wrought-iron or other suitable material, and rendered ornamental by tinning, plating, or like means well known in the arts.

When it is desired to apply the coupler, the set-screw s is loosened and the sections d d' drawn out or forced together until the coupler is the desired length, after which the set-screw is tightened to secure the sections. The pivoted tongues or keepers g are then opened, and, the yokes f being placed around the fellies of the front and hind wheels, (or any 90 two wheels,) the keepers are closed to secure the wheels, and the same, being thus coupled by the coupling-rod D d d', can no longer revolve, which reduces the vehicle to a drag, and prevents the ready removal of the vehicle 95 from place to place and the liability to damage from the running away of teams which have been left untied.

I do not herein broadly claim a device for coupling wheels having an extensible coupling-rod and wheel-yokes; but

What I do claim, and desire to secure by Letters Patent, is—

1. A device for coupling the wheels of a ve-

hicle, consisting of a coupling-rod provided at its extremities with yokes having pivoted spring locking-keepers, substantially as and for the purposes specified.

5 2. A device for coupling the wheels of vehicles, consisting of an extensible sectional coupling-rod provided at its extremities with yokes having pivoted spring locking-keepers, substantially as and for the purposes specified.

10 3. The combination, with a wheel-coupling rod provided at its extremities with yoke-

yokes, of protective sleeves arranged on the arms and keeper of the yoke, substantially as and for the purposes specified.

In testimony whereof I affix my signature in presence of two witnesses.

WILLIAM L. McDougall.
